UNITED STATES PATENT OFFICE.

HEINRICH KOPPERS, OF ESSEN-ON-THE-RUHR, GERMANY, ASSIGNOR TO H. KOPPERS COMPANY, OF CHICAGO, ILLINOIS, A CORPORATION.

METHOD OF OPERATING GAS-PRODUCERS.

1,146,627.

Specification of Letters Patent. Patented July 13, 1915.

Application filed July 27, 1914. Serial No. 853,349.

To all whom it may concern:

Be it known that I, HEINRICH KOPPERS, residing at Moltkestrasse 29, Essen-on-the-Ruhr, Germany, have invented certain new 5 and useful Improvements in the Method of Operating Gas-Producers, of which the following is a specification.

The object of this invention is to provide an improved method of operating gas producers with continuous withdrawal of the slag in a liquid state. According to my invention this is effected by causing part of the 10 hot gases to pass through the discharge passage or passages for the slag, so that the solidification of the slag is prevented by direct heating thereof.

The great advantages to be derived from withdrawal of the slag in a liquid state are frequently counterbalanced, at least in part, 15 by obstruction of the discharge passage, or of the whole under-part of the producer, by solidification of the slag, and the re-liquefying of the slag which in such cases is necessary causes very serious interruption of the 20 work. For obviating this, the hearth has in some cases been artificially heated, in order to maintain the slag in a liquid state, but the arrangements for this purpose are 25 inconvenient and have not obtained complete success in practice.

According to my invention a portion of the gas generated is taken from the upper part of the producer and led downward over the hearth. This not only obviates the necessity for artificial heating of the slag, but the direct heating of the slag by the gas 30 produces the desired result in a most efficient manner. The passage of the gas through the slag discharge orifice in itself assists in preventing obstruction of this orifice.

For further utilizing that portion of the gas which has been used as described, it is of advantage to provide the producer with 45 a chamber into which the slag discharge passage leads, similar to the outer hearth of a cupola in foundry practice. The gas is taken from this chamber for further use. For heating this chamber, the gas may be 50 burnt therein, the products of combustion being blown into the incandescent layers in the producer, in which the carbon dioxid is reduced to carbon monoxid, in the known manner. A continuous circulation of a certain quantity of gas from the producer,

through the slag discharge orifice and outer chamber, and back to the producer, is thus obtained. The heat of gas is utilized, and the gas is recovered or regenerated after being burnt in the outer chamber.

Apparatus suitable for carrying the invention into effect is shown in the accompanying drawings, in which—

Figure 1 is a cross section thereof; Fig. 2 is a cross section to a larger scale, showing a special construction of the outer chamber.

The shaft *a* of the producer is of the usual type, with a blast pipe *b* and twyers *c*. The hearth *d*, which may have a flap door and a trough for separated iron, is provided with 70 a slag discharge passage or duct *e*, leading to an outer chamber *f*. A pipe *g*, with a steam injector *h*, connects the chamber *f* to the shaft *a*.

A portion of the very hot gases formed in 75 front of the twyers *c* is taken through the duct *e* to the chamber *f*, and these gases (or their products of combustion, if they are burnt in the chamber *f*) are forced from the chamber *f* through the pipe *g* to the producer, by the injector *h*. The slag is thus heated and maintained in a liquid state, and the passage through the duct *e* is kept clear. Such carbon dioxid as is present in the gas, either due to partial combustion in the 80 chamber *f*, is reduced to carbon monoxid upon issuing from the pipe *g* into the producer. The heating of the slag is thus effected practically without loss, as the gas is restored to the producer, together with the 85 heat not given off by the same to the slag.

In the construction shown in Fig. 2 the outer chamber is formed by a bell or dome *f* sealed by partial immersion in water in a tank *k*. This arrangement affords several 90 advantages. The sealing of the chamber automatically adjusts itself to varying pressures and the liquid slag, dropping into the water, is granulated and reduced to a state in which it can be most conveniently removed, either by means of hand implements or by a mechanical conveyer, or it may be swept out of the tank by means of a stream of water flowing through the tank. In this case also the producer *a* has twyers *c* delivering air from the blast pipe *b*. The slag descends on to the sloping hearth *d* and flows through the passage *e* into the interior of the bell or dome *f*, from which it drops into the water, and is at once cooled and granulated.

lated. The gas which issues from the passage *e* remains over the water level in the bell *f*', and this water level adjusts itself, in relation to the water level outside the bell, according to the pressure of the gas. No combustion of the gas for heating purposes takes place in the bell, and the gas can be taken through a pipe back to the producer. As the gas pressure at the upper part of the producer is lower than that at the bottom, owing to the intervening fuel, no artificial pressure is required in order to return the gas from the bell to the producer.

What I claim as my invention and desire to secure by Letters Patent of the United States is:—

1. The method of operating a gas producer with discharge of the slag in a liquid state, which consists in causing a portion of the hot gas generated to pass with the slag through the slag discharge passage.

2. The method of operating a gas producer with discharge of the slag in a liquid state, which consists in causing a portion of the hot gas generated to pass with the slag through the slag discharge passage, and in receiving said portion of the gas in an outer chamber.

3. The method of operating a gas producer with discharge of the slag in a liquid state, which consists in causing a portion of the hot gas generated to pass with the slag through the slag discharge passage, in re-

ceiving said portion of the gas in an outer chamber, and returning same to the producer.

4. The method of operating a gas producer with discharge of the slag in a liquid state, which consists in causing a portion of the hot gas generated to pass with the slag through the slag discharge passage, in receiving said portion of the gas in an outer chamber, and returning same to the producer by means of an injector.

5. The method of operating a gas producer with discharge of the slag in a liquid state, which consists in causing a portion of the hot gas generated to pass with the slag through the slag discharge passage, and in receiving said portion of the gas in an outer chamber in which the slag is simultaneously quenched and granulated.

6. The method of operating a gas producer with discharge of the slag in a liquid state, which consists in causing a portion of the hot gas generated to pass with the slag through the slag discharge passage, and in receiving said portion of the gas in an outer chamber in which the slag is simultaneously quenched and granulated, the quenched slag being removed through the seal formed by the quenching liquid.
